(57) CLAIM

I claim the ornamental design for outsole, as shown and described.

DESCRIPTION

FIG. 1 is a bottom plan view of an outsole showing my new design;

FIG. 2 is a left side elevational view thereof;

FIG. 3 is a right side elevational view thereof;

FIG. 4 is a front elevational view thereof; and,

FIG. 5 is a rear elevational view thereof.

The broken line showing a shoe upper in FIGS. 2-5 illustrates the portion of the design that forms no part of the claim.
